(57) CLAIM

We claim, the ornamental design for a display screen or portion thereof with icon, as shown and described.

DESCRIPTION

The FIGURE is a front view of a display screen or portion thereof with icon showing our new design.

The dash-dot broken lines showing the display screen or portion thereof and the even broken lines showing the word "GALAXY" are provided for the purposes of illustrating portions of the article that forms no part of the claimed design.
